UNITED STATES PATENT OFFICE.

FREDERICK G. HALDY, OF STAMFORD, CONNECTICUT, ASSIGNOR TO THE YALE & TOWNE MANUFACTURING COMPANY, OF STAMFORD, CONNECTICUT.

MAGNETIC BRAKE.

No. 874,186.

Specification of Letters Patent.

Patented Dec. 17, 1907.

Application filed June 17, 1907. Serial No. 379,477.

To all whom it may concern:

Be it known that I, FREDERICK G. HALDY, of Stamford, in the county of Fairfield and State of Connecticut, have invented certain new and useful Improvements in Magnetic Brakes; and I do hereby declare the following to be a full, clear, and exact description of the invention, such as will enable others skilled in the art to which it appertains to make and use the same.

My invention relates to an improvement in magnetic brakes and it consists of means operated by a magnetic field energized by the magneto-motive force generated in resistance elements, for controlling a brake.

My invention further consists in the parts and combinations of parts as will be more fully explained and pointed out in the claims.

In the accompanying drawings, Figure 1 is a view in side elevation, showing a part of the motor, and Fig. 2 is an end view of same.

1 represents a portion of the motor frame of an electric motor, carrying bracket 2 to which the hood 3 is hinged at 4. This hood carries a series of soft steel or iron studs 5, each carrying a tube 6 properly insulated, with resistance wire wound on it. The studs 5 project from the ends of the spools adjacent to the motor, and are approximately in line with the edge of hood 3 adjacent to the motor frame 1. Hood 3 carries a post 7, carrying spring 8, the latter bearing at one end against the shoulder 9 on the post and at its opposite end against the motor casing 1. This spring tends to normally hold the hood away from the motor casing, thus producing an air gap 10 at one end and a much smaller gap 11 at the upper or hinged end.

Secured to the motor casing 1 and projecting into the hood, is the bracket 12, and secured to the outer plate of the hood 3 and projecting toward the motor frame is the bracket 13, the latter terminating in a plane below the free end of bracket 12 and approximately under same.

Pivotedly secured at its elbow to the bracket 12 is the bell crank lever 14, the short vertical arm of the latter being pivotally connected to the bracket 13, while the longer arm projects horizontally through a slot in the face of the hood and is provided at its free end with a cross head 15 carrying two anti-friction rollers 16.

Passing through the hood 1 is the motor shaft 17 carrying at its free end the brake

pulley 18, which latter is engaged by brake shoes 19 carried by the levers 20. These levers are hinged to a boss on the motor and are preferably curved at their upper ends to conform to the periphery of the pulley 18, the lower ends of the levers being substantially straight and each is provided near its lower free end with the cam plates 21, having downwardly converging faces which are adapted to be engaged by the anti-friction rollers 16.

Passing through the brake levers 20 is the rod 22 carrying springs 23 held in place by nuts, the said springs bearing against the outer faces of the levers 20, and yieldingly holding the brake shoes in contact with the pulley 18, hence when the hood 3 is in the position shown in Fig. 1, that is to say when the hood is held away from the motor frame 1 by the spring 8, the anti-friction rollers 16 are above, and out of contact with the cam plates 21, thus permitting the springs 23 to force and hold the brake shoes in contact with the pulley. As the hood swings inwardly toward the motor frame, the bell crank-lever 14 will be turned on its fulcrum in a direction to force the anti-friction rollers 16 downwardly into contact with the cam plates 21, and thus spread the levers 20 and release the pulley. As the hood swings outwardly from the motor frame, the anti-friction rollers 16 move upwardly on the cam plate 21, thus permitting the levers 20 to carry their brake shoes into contact with the face of the pulley 14.

This brake is designed more particularly for motors for hoisting purposes, and while it may be used with any motor, I will refer to it simply in connection with the plain series motor, which is the usual type employed for hoisting.

In the operation of the device the hood 3 is so hinged, that when held away from the motor frame 1, an air gap 10 is formed, gradually decreasing in width to the upper end 11. As the hood moves toward the motor frame, gradually reducing the air gap to zero, it will, by means of the bell-crank-lever 14, open the brake levers 20 and release the pulley 18 on motor shaft 17. In starting the motor, the rush of current is cut down by means of the inserted resistance elements 6, and these elements are so wound and connected, that the magneto-motive force generated by the current passing through the resistance coils on

tubes 6, energize the cores 5 accumulatively, thereby attracting motor frame 1. The circuit of the magnetic lines of force is indicated by the dotted lines x.

5 It is a well known fact that when the air gap between magnetized metals is reduced to zero, a comparatively small magneto-motive force is required to maintain the same magnetic pull, providing it is a complete iron circuit as in the present instance; hence after the series resistance has been cut out, comparatively little shunted resistance would produce sufficient magnetic lines of force to hold hood 3 against frame 1 in opposition to the springs 8 and 23, which as before explained tend to increase the air gap and set the brake.

In the ordinary solenoid brake the amount of wire wound on the spool is determined by 20 the magneto-motive force necessary to overcome the reluctance of the air gap when the cores are apart and the brake shoe set. In the present instance, the magneto-motive force is furnished without any extra coil, by 25 means of magneto-motive force generated in the resistance element when the current is first thrown on. In some electric hoists a shunted resistance is employed for controlling no load and light load speeds, which I 30 propose to utilize for maintaining the magnetic field after the series resistance has been cut out.

It is evident that many slight changes 35 might be resorted to in the relative arrangement of parts shown and described without departing from the spirit and scope of my invention, hence I would have it understood that I do not wish to confine myself to the exact construction of parts shown and described, but,

Having fully described my invention what I claim as new and desire to secure by Letters-Patent, is:—

1. The combination of an electric motor 45 and a brake, of a movable electrical resistance device interposed between the brake and motor and included in the circuit of the latter, said resistance device coöperating magnetically with the brake and coöperating 50 mechanically with the brake to control the latter.

2. The combination of an electric motor, a movable resistance device comprising coils having iron cores to coöperate with the motor

structure, and a mechanical brake connected 55 with and operated by said movable resistance device.

3. The combination with a motor case and a movable plate or hood located in proximity thereto, of a resistance element comprising a 60 series of coils having cores of magnetic material, the poles of which are located in position to attract the motor case, and a brake actuated by said movable plate or hood.

4. The combination of a movable resistance element for electric motors and a brake for the motor shaft, the coils of said resistance element having cores of magnetic material, a stationary element to be attracted by said cores, and means connecting the movable resistance element with the brake for controlling the operation of the latter.

5. The combination of a motor frame a 75 resistance element hinged thereto, the coils of said resistance element having cores of magnetic material adapted to attract the motor frame, a brake for the motor shaft and means connecting the hinged resistance element with the brake for controlling the movement of the latter.

6. The combination with a motor frame and a motor shaft, of a resistance element or rheostat hinged to the motor frame and having cores of magnetic material adapted to attract said frame, means normally tending to hold the resistance element out of contact with the frame, a brake for the motor shaft and means actuated by the movement of said resistance element for applying and releasing the brake.

7. The combination with a motor frame and a motor shaft, of a resistance element hinged to the motor frame and having cores of magnetic material adapted to attract said frame, means normally tending to hold the resistance element out of contact with the frame, a brake carried by motor and normally braking the motor shaft and means actuated by the movements of the latter toward the motor frame for releasing the brake.

In testimony whereof, I have signed this specification in the presence of two subscribing witnesses.

Letters Patent No. 874,186.

It is hereby certified that in Letters Patent No. 874,186, granted December 17, 1907, upon the application of Frederick G. Haldy, of Stamford, Connecticut, for an improvement in "Magnetic Brakes," an error appears in the printed specification requiring correction, as follows: In line 49, page 2, the word "brake" should read *motor*; and that the proper correction has been made in the files and records of the Patent Office, and is hereby made in said Letters Patent.

Signed and sealed this 14th day of January, A. D., 1908.

tubes 6, energize the cores 5 accumulatively, thereby attracting motor frame 1. The circuit of the magnetic lines of force is indicated by the dotted lines x.

5 It is a well known fact that when the air gap between magnetized metals is reduced to zero, a comparatively small magneto-motive force is required to maintain the same magnetic pull, providing it is a complete iron circuit as in the present instance; hence after the series resistance has been cut out, comparatively little shunted resistance would produce sufficient magnetic lines of force to hold hood 3 against frame 1 in opposition to the springs 8 and 23, which as before explained tend to increase the air gap and set the brake.

In the ordinary solenoid brake the amount of wire wound on the spool is determined by 20 the magneto-motive force necessary to overcome the reluctance of the air gap when the cores are apart and the brake shoe set. In the present instance, the magneto-motive force is furnished without any extra coil, by 25 means of magneto-motive force generated in the resistance element when the current is first thrown on. In some electric hoists a shunted resistance is employed for controlling no load and light load speeds, which I 30 propose to utilize for maintaining the magnetic field after the series resistance has been cut out.

It is evident that many slight changes 35 might be resorted to in the relative arrangement of parts shown and described without departing from the spirit and scope of my invention, hence I would have it understood that I do not wish to confine myself to the exact construction of parts shown and described, but,

Having fully described my invention what I claim as new and desire to secure by Letters-Patent, is:—

1. The combination of an electric motor 45 and a brake, of a movable electrical resistance device interposed between the brake and motor and included in the circuit of the latter, said resistance device co-operating magnetically with the brake and co-operating 50 mechanically with the brake to control the latter.

2. The combination of an electric motor, a movable resistance device comprising coils having iron cores to co-operate with the motor

structure, and a mechanical brake connected 55 with and operated by said movable resistance device.

3. The combination with a motor case and a movable plate or hood located in proximity thereto, of a resistance element comprising a 60 series of coils having cores of magnetic material, the poles of which are located in position to attract the motor case, and a brake actuated by said movable plate or hood.

4. The combination of a movable resistance element for electric motors and a brake for the motor shaft, the coils of said resistance element having cores of magnetic material, a stationary element to be attracted by said cores, and means connecting the movable resistance element with the brake for controlling the operation of the latter.

5. The combination of a motor frame a 75 resistance element hinged thereto, the coils of said resistance element having cores of magnetic material adapted to attract the motor frame, a brake for the motor shaft and means connecting the hinged resistance element with the brake for controlling the movement of the latter.

6. The combination with a motor frame and a motor shaft, of a resistance element or rheostat hinged to the motor frame and having cores of magnetic material adapted to attract said frame, means normally tending to hold the resistance element out of contact with the frame, a brake for the motor shaft and means actuated by the movement of said resistance element for applying and releasing the brake.

7. The combination with a motor frame and a motor shaft, of a resistance element hinged to the motor frame and having cores of magnetic material adapted to attract said frame, means normally tending to hold the resistance element out of contact with the frame, a brake carried by motor and normally braking the motor shaft and means actuated by the movements of the latter toward the motor frame for releasing the brake.

In testimony whereof, I have signed this specification in the presence of two subscribing witnesses.
